Attorney, Agent, or Firm—Davidson C. Miller

[57] CLAIM

The ornamental design for a magnetic medical necklace, substantially as shown and described.

DESCRIPTION

FIG. 1 is a perspective view of a magnetic medical necklace showing my new design it being understood that the continuous chain is omitted over the path of the dot-dash line for convenience of illustration;

FIG. 2 is a bottom plan view of the magnetic medical necklace;

FIG. 3 is a front elevational view of the magnetic medical necklace;

FIG. 4 is a left side elevational view of the magnetic medical necklace;

FIG. 5 is a right side elevational view of the magnetic medical necklace; and

FIG. 6 is a cross-sectional view taken along line VI—VI of FIG. 2.

FIG. 4**FIG. 5****FIG. 1****FIG. 6****FIG. 2****→ VT****FIG. 3**
